DESIGN FOR A LACE

Henry Giebel, New York, N. Y.

Application January 23, 1940, Serial No. 89,649

Term of patent 3½ years

To all whom it may concern:

Be it known that I, Henry Giebel, a citizen of the United States of America, residing in New York city, in the Borough of Manhattan, county and State of New York, have invented a new, original, and ornamental Design for a Lace, of which the following is a specification, reference being had to the accompanying drawing, forming part thereof, wherein the figure is a plan view of a piece of lace showing my new design.

I claim:

The ornamental design for a lace, substantially as shown.

HENRY GIEBEL.
